UNITED STATES PATENT OFFICE

STANLEY M. HALLAM, OF MILWAUKEE, WISCONSIN

DESIGN FOR A CLOCK LAMP

Application filed October 4, 1930. Serial No. 37,135. Term of patent 3½ years.

To all whom it may concern:

Be it known that I, STANLEY M. HALLAM, a citizen of the United States, and a resident of Milwaukee, in the county of Milwaukee and State of Wisconsin, have invented a new, original, and ornamental Design for a Clock Lamp, of which the following is a specification, reference being had to the accompanying drawing, forming part thereof.

The figure is a front perspective view of the clock lamp, the opposite side of the article being similar to the side shown in the present figure with the exception, that the rear face of the clock is devoid of ornamentation.

I claim:

The ornamental design for a clock lamp, as shown and described.

In testimony that I claim the foregoing I have hereunto set my hand at Milwaukee, in the county of Milwaukee and State of Wisconsin.

STANLEY M. HALLAM.
